APPARATUS FOR GENERATING LARGE
MECHANICAL VIBRATIONS

Edward W. Smith, Melrose Highlands, Mass.

Application December 14, 1949, Serial No. 132,967

10 Claims. (Cl. 310—29)

1

The present invention relates to apparatus for generating vibrations of large amplitudes over an extended surface to be used for the removal of liquids held in sheet materials and in drying of materials such as paper, plastics, fabrics, textiles and the like; capable of absorbing moisture whether from water or other liquids, as well as for the impregnation of materials having large surface areas. The device in the latter case may be applied to the impregnation of the same sort of materials and also may be applied to dyeing or other treatment of paper, cloth fabric, plastics or the like in aqueous or other liquid solutions.

In the methods heretofore used for the removal of water from paper, it has been common to pass the paper through a calender or squeeze rolls and this method has also been applied to the processing of other sheet materials. The application of pressure for this purpose is not always suitable because of the action of the pressure in compressing the sheet which may change its character as for instance if permanent distortion occurs by some other action on the fibers or other elements forming the sheet material.

In the method employed in the present invention, water or other liquids, passed over or in close contact with a vibrational surface of large amplitudes, may give a remarkably high acceleration. For instance the vibration of a body at a frequency of 360 cycles per second and at an amplitude of $\frac{1}{2}$ inch involves a maximum acceleration of around 500 g. or in other words, 500 times the acceleration of gravity. When forces of this nature are applied to paper for an appreciable interval, the water is effectively removed by actually throwing the water particles away from the sheet or if the sheet is in intimate contact with a liquid, vibrating with such amplitudes, the liquid will be made to penetrate or be forced into the sheet.

Amplitudes of $\frac{1}{2}$ inch at 360 cycles per second and higher are considered large amplitudes. Where the vibrating surface has widths of approximately 2 feet and more, as for instance widths from 10 feet to 15 feet, the vibration of the surface with an amplitude of $\frac{1}{2}$ inch produces extremely large volumetric amplitudes of vibrations. In the specification and claims of the present invention, such amplitudes of $\frac{1}{2}$ inch for 360 cycles per second or more and vibrations of large surfaces as above specified at amplitudes of $\frac{1}{2}$ inch are all considered large mechanical amplitudes.

One of the objects of the present invention is to construct a device by means of which a sheet

2

of substantial width, for example 160 inches or wider may be operated upon with the forces above described.

Another object of the present invention is to construct a device which can treat a sheet when continuously fed.

In the device of the present invention, I prefer to employ comparatively low frequencies, that is in the range of about 60 cycles to approximately 500 cycles rather than in the supersonic range above 10,000 cycles and to use a balanced system so as to eliminate the necessity of a rigid or solid base for supporting the vibratory apparatus.

The invention will be more fully described in the specification below when taken in connection with the drawings illustrating an embodiment of the invention in which—

Figure 1 shows a perspective view of the apparatus used in the present invention with parts shown in fragmentary section.

Figure 2 shows a detail of the magnet system for generating the mechanical oscillations, and Figure 3 shows in section a modification of a detail of Figure 1.

In the arrangement indicated in the figures, the vibratory surfaces are formed with large similar plates 1 and 2 of steel or other material having a high elastic modulus, positioned parallel with one another. These plates are supported by a series of metallic tubes 3, 3, 3, which are arranged with axes parallel to each other and which may extend substantially the length or width of the plates. The tubes 3 are chosen of highly elastic material with diameter and wall thickness chosen in such a manner that the force applied across the diameter with, for example, a one inch linear length or other chosen unit length of the tube will cause a deflection of the tube of an amount equal to twice the desired amplitude of vibration of the two plates. The tubes 3, 3, 3, have attached at their top and bottom external surfaces base members 4, 4, which comprise a milled or formed, dove-tail element which fits with a tight fit in a correspondingly cut groove on the under side of the plates. The flange or tapered base members 4 extend preferably the whole length of the tubes 3 and should have such a close and rigid fit that there is no looseness between the tubes and the plates when the apparatus is vibrating. This may be accomplished by the use of a forced fit joint or by expanding the groove slightly by heat before the tube is inserted. One must be careful in this connection, however, not to put excessive

stress upon the material of the plate since the plates 1 and 2 should vibrate as closely as possible in the same phase over their entire surfaces. The plates 1 and 2 because of the balanced system will be 180° out of phase with one another, that is, both plates 1 and 2 will be moving simultaneously outwards and then simultaneously inwards. While in Figure 1, three metallic tubes are shown, it will be appreciated that the present type of system may be expanded both in length and width by adding more tubes and having tubes of greater length. Between the tubes is the electromagnetic system. This comprises a set of E-shaped laminations 5, which may be secured by desirable means to the inside of the plate 1, either directly or indirectly. In Figure 1, this is done through an intermediate plate 6, to which the laminations 5 are welded, the plate 6 itself being welded or secured in a suitable way to the under side diaphragm 1. The E-shaped laminations are stacked in alignment parallel to the tubes 3 and between each set of tubes a magnetic structure, as described below, is located.

A coil 7 (see Figure 2), is placed in the recesses of the laminations threading around the center pole elements 8. In Figure 1, the opposing magnetic element comprises an aligned stack of plain laminations 9 which may be welded along their stacked edges to the plate 10 which in turn is secured to the support 11 attached to the inside of the plate 2. The laminations 9, the plate 10, and the support 11, are all held together as a rigid structure and are rigidly attached to the inside of the plate 2. The magnetic structure attaching to the base 2, may however, be similar to the magnetic structure attached to the bottom of the plate 1.

This is shown in Figure 3 where the plates 1 and 2 each carry a stack of aligned E-shaped laminations 5 and 12, with coils 7 and 13 extending longitudinally in the slots or recesses of the laminations. When alternating current is passed through the coil 7 (Figure 2) or through the coils 7 and 13 (Figure 3), a force is set up between the armatures or across the air gaps which produces a vibration of the plates. This force is applied to the plates between each of the longitudinal tubes along a length parallel to the tubes and substantially for the whole length of the diaphragm. The vibrations so applied set up vibrations in the tubes which are substantially in a direction perpendicular to the plane of the vibrating plates 1 and 2, and thereby exert in the walls of the tubes, a compressional and bending force which by proper choice of the character of the material of the tube and its thickness and size with respect to the masses of the plates, may be made to resonate at a desired resonant frequency. The vibrations of the plates 1 and 2 will be of a so-called piston type with the greatest linear amplitude of vibration in the region where the magnetic force is applied but with a vibration not substantially less in the region of the tubes, particularly at resonance. The plates 1 and 2 may be of the order of $\frac{1}{2}$ " in thickness, for example, and therefore comparatively stiff to transverse surface vibrations and the mean diameter of the tubes 3 may be 2" with a wall thickness of .085". With a magnetic stator and armature, as shown in Figure 1, the system may be made to resonate at about 360 cycles, which means that at such a frequency the device will operate at the greatest impressed energy. Since the device of Figure 1 is often used to operate

in a liquid medium, it is preferable to seal the apparatus by a seal extending all around the edges. Such a seal is indicated in Figure 1 where a soft resilient sheet 14, which may be of rubber or plastic material is held tightly against the edges of the plates 1 and 2 by means of bands 15 and 16. A cable connection may be made through the resilient sheet 14 for supplying the coils in the E-shaped laminations with alternating current. The ordinary alternating sinusoidal current will produce vibrations of the electromagnetic system of the same type and also similar vibrations of the piston acting plates in opposing phases of 180°.

In the present invention, the device may be used in many different ways. It may be used for the purpose of impregnating or dyeing sheet or other materials, in which case the apparatus may be suspended in a tank filled with the liquid impregnating material and the sheet may be passed over the vibratory surfaces. The sheet may be fed into the tank downward close to one vibratory face and up close to the opposite vibratory face. The device may also be used for drying purposes and is particularly adaptable for use in expelling liquids from solid sheets of paper, plastics, fabrics of woven, knitted, or other construction. The word "solid" in this case is used in the sense of contrast with liquids and not in relation to non-porosity of the materials.

In the use of the apparatus in connection with paper, the paper sheet in its manufacture which ordinarily is filled with water, may be drawn over the vibrational surfaces 1 and 2 and the vibration of these surfaces against the water-soaked sheet will expel the water from the sheet. For this purpose, the paper could be held against the vibratory surface by an absorbent belt or web which would take up the moisture thrown off the sheet and thereby enhance drying.

Many other methods may be used in connection with industrial processes involving the present apparatus.

Having now described my invention, I claim:

1. Apparatus for generating large mechanical vibrations comprising a pair of parallel opposed plates, a plurality of tubes, means securing each of said tubes along opposite sides thereof to the opposing faces of the plates in parallel spaced relation one to the other, and electromagnetic means positioned and acting on said plates in the region between tubes for producing periodically repeated forces along substantially the length of the plates in a perpendicular direction between said plates.

2. Apparatus for generating large mechanical vibrations comprising a pair of parallel opposed plates having substantially unrestrained peripheral edges, a plurality of cylindrical tubes, means firmly securing said tubes to the opposing faces of the plates in spaced relation parallel to one edge of said plates, and electromagnetic means positioned in the spaces between tubes extending substantially along their length for vibrating the plates sinusoidally in opposing phases.

3. Apparatus for generating large mechanical vibrations comprising a pair of parallel opposed plates having a high elastic modulus with a thickness of approximately $\frac{1}{2}$ " and having substantially unrestrained peripheral edges, a plurality of cylindrical tubes, means firmly securing said tubes to the opposing faces of the plates in spaced relation parallel to one edge of said plates, and electromagnetic means positioned in the spaces between tubes extending substantially along their length for vibrating the plates sinusoidally in opposing phases.

length for vibrating the plates sinusoidally in opposing phases.

4. Apparatus for generating large mechanical vibrations comprising a pair of parallel opposed plates having substantially unrestrained peripheral edges, a plurality of cylindrical tubes, means firmly securing said tubes to the opposing faces of the plates in spaced relation parallel to one edge of said plates, electromagnetic means positioned in the spaces between tubes extending substantially along their length for vibrating the plates and a yielding flexible material hermetically sealed around the edges of the plates to keep out liquids from entering into the apparatus.

5. Apparatus for generating large mechanical vibrations comprising a pair of parallel opposed plates having substantially unrestrained peripheral edges, a plurality of cylindrical tubes, means firmly securing said tubes to the opposing faces of the plates in spaced relation parallel to one edge of said plates, and electromagnetic means positioned in the space between tubes extending substantially along their length for vibrating the plates sinusoidally in opposing phases, said electromagnetic means comprising groups of E-shaped laminations stacked and aligned with their edges parallel to the tubes, a coil imbedded in the recesses of the E-shaped laminations, means retaining the E-shaped laminations against the inner face of the plate, armature means also formed of a stack of laminations, and means attaching said armature means in opposed relation to the E-shaped laminations against the inner face of the opposing plate whereby when the coil is energized with alternating current, vibratory forces are produced across the magnetic circuit.

6. Apparatus for generating large mechanical vibrations comprising a pair of parallel opposed plates having a high elastic modulus and of a substantial thickness, a plurality of comparatively thin cylindrical tubes, means attached to the outer surface of said tubes at diametrically opposed positions rigidly joining said tubes to the inner sides of said plates, said tubes being arranged parallel to each other, electromagnetic means acting between the inner sides of the plates exerting forces normally thereto along a line parallel with said tubes, said electromagnetic means being positioned between adjacent tubes.

7. Apparatus for generating large mechanical vibrations comprising a pair of parallel opposed plates having a high elastic modulus and of a substantial thickness, a plurality of comparatively thin cylindrical tubes, means attached to the outer surface of said tubes at diametrically opposed positions rigidly joining said tubes to the inner sides of said plates, said tubes being arranged parallel to each other, electromagnetic means acting between the inner sides of the plates exerting forces normally thereto along a line parallel with said tubes, said electromagnetic means being positioned between adjacent tubes, said electromagnetic means comprising an armature element attached parallel to said tubes along the inside of one plate and an electromagnetic element attached in opposed relation to the other

plate, magnetic material comprising stacked groups of laminations with a coil recessed therein.

8. Apparatus for generating large mechanical vibrations comprising a pair of parallel opposed plates having a high elastic modulus and of a substantial thickness, a plurality of comparatively thin cylindrical tubes, means attached to the outer surface of said tubes at diametrically opposed positions rigidly joining said tubes to the inner sides of said plates, said tubes being arranged parallel to each other, electromagnetic means acting between the inner sides of the plates exerting forces normally thereto along a line parallel with said tubes, said electromagnetic means being positioned between adjacent tubes, said electromagnetic means comprising similar stacks of E-shaped laminations attached to the inner sides of said plates along a region parallel to the tubes and between adjacent tubes, said E-shaped laminations having a coil imbedded therein for carrying alternating current.

9. Apparatus for generating large mechanical vibrations comprising a pair of parallel opposed plates having a high elastic modulus and of a substantial thickness, a plurality of comparatively thin cylindrical tubes, means attached to the outer surface of said tubes at diametrically opposed positions rigidly joining said tubes to the inner sides of said plates, said tubes being arranged parallel to each other, electromagnetic means acting between the inner sides of the plates exerting forces normally thereto along a line parallel with said tubes, said electromagnetic means being positioned between adjacent tubes, said electromagnetic means comprising similar stacks of E-shaped laminations attached to the inner sides of said plates along a region parallel to the tubes and between adjacent tubes, said E-shaped laminations having a coil imbedded therein for carrying alternating current, a sheet extending around the edges of the plates sealing the inside of the apparatus from the entrance of liquids.

10. Apparatus for generating large mechanical vibrations comprising a pair of parallel opposed plates, metallic means having a high elastic modulus of the order of steel secured to and between said plates and having contact in continuous parallel lines along opposing inner faces of said plates and electromagnetic means positioned and acting on said plates in the region between said means having a high elastic modulus for producing periodically repeated forces substantially along the length of the plate in a perpendicular direction between said plates.
